UNITED STATES PATENT OFFICE.

HOWARD E. MILLER, OF JOHNSTOWN, PENNSYLVANIA.

SWITCH TONGUE.

Application filed June 3, 1925. Serial No. 34,658.

To all whom it may concern:

Be it known that I, HOWARD E. MILLER, a citizen of the United States, and resident of Johnstown, in the county of Cambria and

5 State of Pennsylvania, have invented certain new and useful Improvements in Switch Tongues, of which the following is a specification.

This invention relates to tongue switches 10 and more particularly to the tongues for such switches, and has for its object the provision of a novel heel pin in the heel portion of the tongues, which pin may be manufactured separate from the tongue 15 and, therefore, have a better finish and be of greater strength than the cast pins formed integral with the cast tongues.

Another object is to provide a tongue switch having the novel construction, design and combination of parts hereinafter described and illustrated in the accompanying drawings.

Switch tongues of the class to which this invention belongs are generally cast from 25 manganese steel and heretofore the heel pins have been cast integral therewith, and considerable difficulty has been experienced in getting a good finish on the pins, and also on the base of the tongues for the area 30 adjacent to the pins, and also due to the fact that in casting such a small projection on such a large mass it was difficult to cast perfect pins. A great percentage of the tongues cast were found to have defective 35 pins and were necessarily scrapped.

Another difficulty is encountered in the casting of switch tongues with integral cast pins, which arises from the fact that manganese castings, as they come out of the sand 40 and before heat treatment, require to be cleaned; that is, the loose sand is removed and the nail heads, fins and other extraneous matter attached to the castings have to be chipped or knocked off with a hammer. At 45 this stage manganese steel is exceedingly brittle and readily breaks. Therefore, during the cleaning process the heel pin is very often broken off accidentally and, of course, destroys the whole tongue.

50 All of the above difficulties are overcome and eliminated by the present invention and a pin having a higher finish and of exceedingly greater strength is provided.

In the drawings:

55 Figure 1 is a top plan of a portion of a switch structure embodying my invention.

Figure 2 is a section on the line II—II of Figure 1.

Figure 3 is a plan of the heel portion of a 60 switch tongue embodying my invention.

Figures 4 and 5 are sectional elevations on the lines IV—IV and V—V of Figure 3 respectively.

Figure 6 is a plan of the removable heel 65 pin.

Figure 7 is a sectional plan of the heel pin.

Referring more particularly to the drawings, the numeral 2 designates the body portion of a standard switch provided with the 70 usual tread and guard surfaces. The body portion 2 is provided with an elongated recess or tongue bed 3 having an enlarged circular recess 3^a to receive the heel 4 of the switch tongue 5.

The heel portion 4 of the tongue 5 is provided with a pin A which is preferably forged to shape from a low carbon steel and machined or otherwise finished. The pin A has a flat square head portion 9 on its inner 80 or upper end and is mounted in the mold prior to the casting of the tongue, so that the head portion will be surrounded by the metal of the tongue, and, therefore, forms an integral part of the cast tongue.

As is well known the heat treatment of manganese steel calls for heating the raw cast manganese steel to a high temperature, approximating 1850 degrees Fahrenheit, and quenching in cold water. Therefore, 90 it is especially important to limit the steel pins A to a low carbon, to guard against undue hardening of the carbon steel pins during the heat treating process.

The pins A have a shank or stem portion 95 10 and a base portion 11.

The pin A is adapted to hold the tongue in perfect bearing in the heel receiving portion 3^a of the tongue bed 3 under conditions of snow, ice or mud. The pin projects 100 through an orifice 12 in the portion 3^a of the bed 3, into a recess 13 below the tongue bed. Mounted within this recess 13 is a lever 14, which is fulcrumed on a projection 15 on the switch body 2. One end of the 105 lever 14, is provided with a fork 16, and the opposite end 17 is provided with a boss which is threaded to receive a screw 18 having a jam nut 19. The forked end 16 of the lever 14 is engaged around the shank 110 or stem 10 of the pin A.

When the parts are assembled the screw

18 is screwed down to its proper place of adjustment and locked by the jam nut 19. As will be readily understood from the drawings, the screw 18 has a tendency to

5 raise the one end of the lever 14, thereby depressing the forked end 16, and with it the heel 4 of the tongue 5.

The advantages of this novel construction of switch tongue will be readily appreciated 10 by those skilled in the art, since it eliminates one of the greatest causes of imperfect castings, it provides a materially stronger construction and is less likely to breakage during transportation or in use.

15 I claim:

1. A cast steel switch tongue having a heel portion, and a forged steel tongue se-

curing pin formed separate from said tongue and permanently secured to the heel portion by casting the tongue around the 20 pin.

2. A cast manganese steel switch tongue having a heel portion, and a forged low carbon steel tongue securing pin formed 25 separate from said tongue, said pin being provided with an enlarged head portion, and being permanently secured to the heel portion by casting the tongue around the pin so that the head of said pin is entirely surrounded by the cast metal of the tongue. 30

In testimony whereof, I have hereunto set my hand.

HOWARD E. MILLER.
